UNITED STATES PATENT OFFICE.

ALBERT D. GOODELL, OF MILLER'S FALLS, MASSACHUSETTS, ASSIGNOR TO MILLERS FALLS COMPANY, OF SAME PLACE.

RATCHET BIT-BRACE.

SPECIFICATION forming part of Letters Patent No. 228,810, dated June 15, 1880.

Application filed March 5, 1880. (No model.)

To all whom it may concern:

Be it known that I, ALBERT D. GOODELL, of Miller's Falls, in the county of Franklin and Commonwealth of Massachusetts, have invented a new and useful Improvement in Ratchet Bit-Braces, of which the following is a full and clear description.

My invention relates to that class of bit-braces to which is attached a ratchet and pawl, to enable one to use a boring-tool or other in a brace when, from its being in a confined position or otherwise, it is convenient to turn the tool in working condition partly around, and turning the handle back without working the tool, the ratchet sliding under the pawl, the tool comes back to a working position, as before.

All of my invention is represented in the accompanying drawings, of which—

20 Figure 1 is an elevation of the brace, partly in section; Fig. 2, a horizontal section on line *x x* of Fig. 1. Fig. 3 is a detail, showing the relation of ratchet to pawl.

All the parts of the bit-brace which hold the 25 boring-tool, as the jaws, the slotted socket in which they work, and the sleeve-nut which retains them, are supported by, secured to, and dependent on a standard, A, which passes through the lower end of the bit-stock in the 30 same plane with the handle and the breast-piece or head, and also through the ratchet B, which controls the action of the boring, and in which it is secured by a pin, *a*, passing through the ratchet and the standard.

35 The lower end of the bit-stock is slotted at a right angle to the plane of the handle, head, and boring-tool deep enough to receive the ratchet B and pawl C behind it. Back of this slot is drilled a hole, D, deep enough to receive a small helical spring, E, having on its outer end a stud or face, *b*, to bear against the pawl and to keep it in bearing against the ratchet. The ratchet B is a section of a cylinder, having through its center a hole, through 40 which passes the standard A, holding the jaws and sleeve which gripe the boring-tool, and to which it is secured by a pin, *a*, passing through both.

The pawl consists of a small square bar run-

ning in the before-mentioned slot through the 50 lower end of the bit-stock, and at right angles to the plane of the handle and boring-tool. On each end of this bar, and bearing against the outer side of the bit-stock, is a button, G, with a milled edge to afford a grasp whereby to turn 55 the pawl. Within these, and bearing on each edge of the slot, are rounded shoulders H, on the bar, to admit its being turned and to keep it in position. Around the central part of this bar are four projections, one on each side, 60 which form the pawl operating on the ratchet by dropping in turn into the square-faced notches on the edge of the ratchet, holding it when turned in one direction, and yielding when turned in an opposite. Two of these 65 projections on opposite sides of the bar have a square flush face, and as they respectively are let into the notches on the ratchet hold it fast from turning in either direction. On the other two sides of the bar one of the projections is beveled from a square face down to the bar toward the right, and the one on the opposite side of the bar toward the left, so that when the ratchet, 70 which is attached to the boring-tool, is turned in one direction the square face of the notch 75 in it engages on the square edge of the pawl, and the boring-tool is turned; but if the ratchet is turned the other way the edge of the notch slides up each of the inclined sides of the projection on the bar forming the pawl till the 80 handle of the bit-stock is turned back, as desired, when it is ready, on being again turned forward, to catch the face of the pawl and hold. The projections on the two opposite sides of the bar being beveled, one to the right and the 85 other to the left, form the pawl, and as it is turned so as to present the one or the other face to the ratchet, so it will operate to work the tool either to the right or to the left.

The buttons on each end of the bar forming 90 the pawl are marked in the proper places "R." and "L." to indicate how the pawl is to be set to work the tool to the right or left.

The pawl is kept up against the ratchet by the force of the coiled spring with a head let 95 into the bit-stock behind it.

The four corners of the inclined projections forming the pawl are all beveled off a little to

admit their easy working over the notches forming the teeth of the ratchet and on the face of the spring.

The inner faces of the slot receiving the 5 pawl are worked out to allow a sufficient space for the points forming the pawl to turn.

The operation of this device is as follows: The boring or other tool being secured in the socket, the buttons on the end of the pawl, or 10 one of them, is turned so that the letter on its face points outwardly toward the ratchet. If it is the letter R the tool will work from the left to the right, and the handle return free.

If the letter L is pointed out the tool will cut 15 from right to left. If the button is set with

either of the intermediate spaces toward the ratchet the bit-stock and tool will be rigidly fixed and work as an ordinary bit-stock.

What I claim, and desire to secure by Letters Patent, is—

In a ratchet bit-brace, the pawl C, having its spindle provided with rectangular and oblique faces on opposite sides, in combination with ratchet-wheel B, bearing-plate b, spring E, and bit-stock A, as and for the purpose set 25 forth,

A. D. GOODELL.
